UNITED STATES PATENT OFFICE.

CHARLES H. WOODWARD, OF BOURNEMOUTH, ENGLAND.

SYSTEM OF SPEED CONTROL.

1,285,876.

Specification of Letters Patent. Patented Nov. 26, 1918.

Application filed October 21, 1915. Serial No. 57,161.

To all whom it may concern:

Be it known that I, CHARLES HEMLET WOODWARD, a citizen of the United Kingdom of England, residing at 15 Richmond Park Crescent, Bournemouth, in the county of Hampshire, England, have invented a new and useful System of Speed Control, of which the following is a specification.

This invention relates to improvements in speed control systems for railway trains for use in conjunction with any system of operative control, as, for instance, an air brake system or a control for the motive power applied to the train.

10 The object of the invention is to permit a train to proceed at any speed under a given limit when running under danger conditions, so constructed and arranged as to stop the train when the pre-determined safety limit of speed is reached or exceeded.

Generally speaking my invention contemplates the use of direct current for the purpose of controlling a train and permitting it to proceed under safety conditions and the use of alternating current to control the train to permit it to proceed at a given limited speed under danger conditions. That is to say,—the train may be equipped with the usual or any known direct current train control system which is operative to permit the train to proceed at any desired speed on a safe track, and which becomes effective under danger conditions, as when the train enters a block which is already occupied by another train, or on which there is an open switch, a broken rail, or the like, to stop or slow down the train, by opening the release valve of the air brake system, or to cut off the motive power, or both. In

40 addition to such or like controlling systems which may be used, I propose to employ an alternating current circuit which is connected to the control device in such a way that it will assume control of said control device when the speed of the train has been reduced to a predetermined speed and thereafter permit the train to proceed under danger conditions within the predetermined slow speed, but when the train exceeds such limited

50 speed under danger conditions the alternating circuit will be effective to permit the control device to be actuated and stop the train. The alternating current circuit may be supplied by current from a constant volt 55 alternating current generator that is geared to one of the train axles in such a way that

the frequency of the alternating current changes with the speed of the train and the consequent variation of impedance in the alternating current circuit finally becomes 60 sufficient to cause the train control device to be operated to stop the train.

In one embodiment of the invention as applied to an air brake system, the release valve of the brake pipe may be held up 65 against its seat, against the action of gravity, by windings in the circuits when said windings or either of them are energized, and drops by gravity away from its seat when the windings are deenergized. In 70 such an arrangement the direct current circuit winding is operative under safe conditions, and at any speed, to hold the valve against its seat, and the winding of the alternating current circuit is operative to hold 75 the valve against the seat only when the train is traveling at a predetermined slow speed. Therefore, when the valve is released by the direct current winding, it will open and apply the brakes, unless the train be 80 traveling within the range of speed at which the alternating current winding is operative to assume control of the valve. If the train be running at high speed when the valve is opened it will be slowed down by the application 85 of the brakes until it has attained a speed at which the alternating current winding becomes effective to close the valve. The train may therefore be operated under danger conditions until it exceeds the prescribed 90 limit, whereupon the alternating current winding is deenergized and the valve is opened to apply the brake.

I have shown in the drawing diagrammatically the elements of my novel train 95 control system, as applied to a train equipped with an air brake system, but it will be understood that the invention is capable of assuming other specific arrangements and may be applied to other control 100 devices of the train without departure from the spirit of the claims hereto appended.

In said drawings:—

The figure illustrates one embodiment of 105 my invention.

10, 11 designate respectively the wires from an ordinary train control circuit. They are connected to a relay 12 of a local circuit, carried by the train, in which is included a battery 14 and a winding 15.

16 designates the brake pipe of an air 110 brake system and 17 designates a valve

which normally seats upwardly against a valve seat 18 in a valve casing 19 that is connected with the pipe in any usual way. The valve casing is provided below its seat 5 with a lip 20 which limits the drop of the valve away from its seat.

The stem 21 of the valve is provided at its lower end with a core 22 which operates in the direct current winding 15. The winding is so proportioned to the weight of the valve and the core that when the local circuit including the battery 14 is closed by the relay 12, the valve 17 is forced upwardly against its seat to close the brake pipe. 10 When said winding is deenergized the weight of the valve and the core causes the valve to drop away from its seat and open the brake pipe to apply the brakes.

In addition to the control circuit described, the core 22 is wound with a second winding 23. The said winding 23 is connected through a circuit 24 to a constant volt alternating current generator 25, which is driven in any suitable manner from one 25 of the axles 26 of the train,—as, for instance, by means of a pulley 27 fixed to and rotating with the axle and connected to the shaft of the generator by a belt 28. The frequency impressed upon the circuit 24 of 30 the constant volt alternating generator is proportioned to the speed of the train so that the increased impedance caused by the increased frequency, due to the speed of the train, can be used to decrease the lifting effect of the winding 23 on the core 22 to 35 such an extent that when the train is running beyond a prescribed speed said winding will be ineffective to hold the valve against the seat.

40 Normally and under safety conditions, the direct current winding is relied upon to hold the valve 17 closed. When this condition alters to danger, as when the train enters a block occupied by another train or is modified by other danger conditions, the direct current winding ceases to act, whereupon the valve 17 opens and the brakes are applied, and this condition continues until the decreasing speed of the train reduces the 45 alternating current frequency of the circuit 24 to a point at which the alternating current winding 23 operates. Thereupon the brake valve is again raised to its closed position and the valve will remain closed so as to release the brakes as long as the speed 50 of the train is kept below the pre-determined limit. It is clear that any failure of the auxiliary apparatus will apply the danger condition in the same way that failure of the 55 main train circuit will apply or indicate danger conditions.

Moreover I may employ other specific arrangements of releasing valve mechanism for releasing the air from the train pipe 60 in which gravity is not relied upon to open

the valve. The invention is not intended to be limited to the specific details shown and described, except as the same are made the subject of specific claims.

I claim as my invention:—

70 1. A control system for railway trains embracing a train control device, a direct current control circuit therefor, and an alternating current control circuit for said device constructed with means for taking control of said device to permit the train to operate at a pre-determined slow speed when the direct current circuit is inoperative.

2. A control system for railway trains 80 having a direct current control circuit and an alternating current control circuit for controlling the train when the direct current circuit is inoperative, with means to vary the frequency of the latter circuit with the 85 speed of the train to thereby change the effectiveness of impedance in said circuit.

3. A speed control system for railway trains having a train control device, with a direct current control circuit to operate the 90 same for safety conditions, and an alternating current control circuit having means to permit the train to proceed at a limited speed under danger conditions.

4. A speed control system for railway 95 trains having a train control device with a direct current control circuit to operate the same for safety conditions, and an alternating current control circuit having means to permit the train to proceed at a limited 100 speed under danger conditions, with means controlled by the speed of the train to render the alternating current control circuit inoperative when the train exceeds a predetermined speed.

105 5. A speed control system for railway trains having a train control device, with a direct current control circuit to operate it for safety conditions, an alternating current generator driven by the movement of the 110 train and a circuit supplied by current from said generator and having means to control the train control device under certain speeds of the train when the direct current control circuit is inoperative.

115 6. In a speed control system for railway trains, a train control device operative for stopping the train, a direct current circuit for controlling said device and an alternating circuit for also controlling said device, with means whereby the frequency of the 120 current of the alternating circuit is controlled by the speed of the train.

7. In a speed control system for railway 125 trains, a train control device operative for stopping the train, a direct current circuit for controlling said device, an alternating current generator driven by the movement of the train and having a circuit for actuating said control device, the frequency of 130

- the alternating current being proportioned to and controlled by the speed of the train.
8. In a speed control system for railway trains, a train stopping and speed control device and an alternating current circuit for controlling said device, with means controlled by the speed of the train for varying the frequency of the current of said circuit for the purpose set forth.
- 10 9. A speed control system for railway trains equipped with an air brake system embracing an air release valve, a magnetizable core connected to the air valve, a winding surrounding said core, with a direct current circuit to energize the winding, and a second winding surrounding the core, with an alternating current circuit in which said second winding is included.
- 10 10. A speed control system for railway trains, equipped with an air brake system embracing an air release valve, a magnetizable core connected to the air valve, a winding surrounding said core, with a direct current circuit to energize the winding, a second winding surrounding the core, with an alternating current circuit in which said second winding is included, an alternating current generator driven by the movement

of the train for supplying current to said alternating circuit, the frequency of which is such that the impedance of said alternating circuit is raised to such extent that the winding in its circuit becomes inoperative to control said valve when the train exceeds a predetermined limit of speed.

11. In a train control system, the combination with an air brake system including a brake pipe, with a release valve in said pipe which opens by gravity, of a magnetizable core connected to the stem of said valve, a winding surrounding said core and connected to a direct current control circuit, a second winding surrounding the core, an alternating current circuit in which the second winding is included, and means to vary the frequency in the alternating circuit by the speed of the train whereby the impedance in the alternating circuit increases to such extent, when the train reaches a predetermined speed, as to render said second winding inoperative to control the valve.
